UNITED STATES PATENT OFFICE.

ERNEST G. NUFFER, OF PHILADELPHIA, PENNSYLVANIA, ASSIGNOR TO
GEORGE BROOKS & SON, OF SAME PLACE.

DESIGN FOR A CURTAIN FABRIC.

SPECIFICATION forming part of Design No. 15,683, dated January 6, 1885.

Application filed November 24, 1884. Term of patent 3½ years.

To all whom it may concern:

Be it known that I, ERNEST GARIBALDI NUFFER, a subject of the Emperor of Germany, residing at Philadelphia, in the county of Philadelphia and State of Pennsylvania, have invented and produced a new and original design for a curtain fabric that may be woven in tapestry, damask, or chenille, and in such colors as may be desired; and I do hereby declare that the photographic print accompanying this specification conveys to any one skilled in the art a clear understanding of

the same, and is sufficient to enable such person to use my invention.

What I claim as my invention, and desire to secure by Letters Patent, is—

The design for a curtain fabric, as shown in the photographic print accompanying this specification.

ERNEST G. NUFFER.
